UNITED STATES PATENT OFFICE.

HARRY LYON, OF BROCKTON, MASSACHUSETTS, ASSIGNOR TO NICHOLS-FIFIELD SHOE MACHINERY COMPANY, OF PORTLAND, MAINE, A CORPORATION OF MAINE,

INSEAM-TRIMMER.

No. 866,150.

Specification of Letters Patent.

Patented Sept. 17, 1907.

Application filed December 19, 1905. Serial No. 292,463.

To all whom it may concern:

Be it known that I, HARRY LYON, of Brockton, in the county of Plymouth and State of Massachusetts, have invented certain new and useful Improvements 5 in Inseam-Trimmers, of which the following is a specification.

The object of the present invention is to provide a machine for cutting to the proper length the inseams of boots and shoes, and which is especially adapted to 10 cut the seam at a uniform distance from the stitches which unite the welt, upper and insole together. In accomplishing this object, I provide a gage which positions the work with reference to the stitches of the inseam instead of with reference to the welt or the crease 15 between the welt and upper.

Another object is to construct a trimming knife of such shape and so arranged as to make a cleaner and better cut and also to assist in firmly holding the work.

The construction by which these objects are attained 20 is more particularly described in the following specification and claims, and is illustrated in the accompanying drawings, in which,—

Figure 1 represents an elevation of the trimming mechanism of an inseam-trimming machine. Fig. 2 25 represents a plan view of the same. Fig. 3 represents a plan view of the parts beneath the line 3—3 of Fig. 1. Fig. 4 represents a perspective view of the same parts. Fig. 5 represents a fragmentary view of the trimming knife and gage, showing in section a lasted shoe applied 30 thereto.

The same reference characters indicate the same parts in all the figures.

Referring to the drawings, 1 represents the upper part of the standard or column of a trimming machine 35 having bearings 2 3 in which is rotatably mounted a shaft 4. An arm or bracket 5 extends from the standard 1 and upon the bracket is mounted a stud 6 which forms a support for a knife-holder 7. The stud is cylindrical and the knife holder has a cylindrical bore 40 fitting over the stud so that the holder may oscillate thereon.

Extending upwardly from the stud is an arm 8 secured to or forming part of the knife-holder and thereto is connected by means of a wrist pin 9 an eccentric rod 45 10 connected to an eccentric strap 11 surrounding an eccentric 12 which is fast to shaft 4. This shaft is rotated continuously by any suitable means, such as the belt pulley 13, and by its rotation through the medium of the eccentric and eccentric rod, produces an oscillatory movement of the knife-holder about the stud 6.

Fixed to the lower part of the knife-holder is a knife blade 14 which is curved circularly about the center of the stud so that when it is oscillated, all parts of the knife travel in paths equi-distant from the stud. The

knife blade 14 forms part of a cylindrical surface and 55 the path in which it oscillates is a continuation of such surface. The preferred construction of knife-holder is that illustrated, which has two arms extending downwardly and substantially radially from the supporting stud. The knife blade 14 is attached to the ends of 60 these arms and consists of a thin curved hoop-like strip.

Pivoted at 15 to the bracket 5 is an arm 16 which constitutes the gage holder and upon the end of which is mounted the gage 17. The latter consists of a thin disk which is pivoted to the end of the holder 16 so as 65 to be capable of rotating freely, and has its periphery serrated to form teeth or pointed projections 18. The gage holder 16 is so mounted that the gage is supported beneath and substantially in the plane perpendicular to the stud 6 in which the knife-holder oscillates. By 70 reason of the pivotal connection between the gage holder and bracket 5, the gage is movable toward and from the knife so as to adjust the distance between them, and it may be fixed in any adjusted position by screwing home the bolt which serves as the pivot 15 and 75 thereby clamping the gage holder against the bracket. 19 is a stop beside the cutting edge 20 of the knife and it consists of a bar passing through the stud 6 and secured by means of a set-screw 21.

Fig. 5 shows the manner in which the machine operates upon a piece of work. In this figure there is shown a partially completed shoe upon a last 22, the upper 23, welt 24 and channel flap 25 of the insole 26 being united together by a line of stitches 27. In order to cut off to the proper length the edges of the welt, 85 upper and channel flap, the lasted shoe is held with the insole uppermost and the crease of the welt through which the stitches 27 pass pressed against the gage 17. As the machine is not encumbered with any clamps or other devices for entering the crease between the 90 welt and upper and holding the gage against the upper side of the welt, the gage is free to bear directly upon the stitches and the projections 18 of the gage are enabled to enter somewhat into the indentations 95 of the seam produced by the awl holes through which the stitches pass. Preferably the serrations of the disk 17 are spaced to correspond with the distance between stitches so that as the shoe is fed past the gage, said serrations will extend into the indentations successively and thus the work will be guided wholly 100 with reference to the stitches. As the gage during any one operation is maintained at a fixed distance from the knife, the stitches also will be held at a constant distance from the knife, and thus the inseam will be trimmed off at a uniform distance at all points 105 from the stitches and there will be no liability either of the stitches being cut or of too much stock being left.

In all the previous machines of which I have

knowledge which trim the inseam of a shoe, the welt serves as the guide by which to position the shoe with respect to the cutter, the gages being usually adapted to enter the crease between the welt and upper of a 5 shoe and made to position the shoe with reference to this crease. When the shoe is so guided, it is not possible to trim the inseam at a uniform distance from the stitches because the different parts of a welt are not of uniform quality and stiffness and are not always positioned in exactly the correct way. Thus at some 10 points the gage is allowed to approach too near the stitches, and again is forced too far away therefrom so that at some points too much stock is left and at others there is too little, and it may even happen in some cases 15 that the stitches are cut. It is impossible for such a result to occur with the construction above described where the gage positions the work wholly and solely with relation to the stitches and entirely independently of the position of the welt. The stop 19 bears 20 against the upper side of the insole and determines the angle of the cut. It also prevents the knife from injuring the insole.

It will be noted that the cutting edge 20 of the knife is oblique to the path in which it oscillates, and that 25 its obliquity is such as to cause it to press upon the work while it is moving toward the gage, this movement being the cutting stroke. This construction causes the knife to press the work against the gage while it is cutting and thereby to hold it more firmly, 30 and it also makes a cleaner and surer cut than would be the case if the edge were exactly parallel to its path of motion.

The plane of the disk which serves as the gage is substantially parallel with that portion of the knife 35 which acts upon the work when the latter is against the gage and thus the resistance of the gage to the pressure of the work is exerted in a direction perpendicular to the axis upon which it is pivoted.

I claim:—

- 40 1. An inseam trimmer comprising a cutter, and a gage arranged to engage the line of stitches of the inseam and hold the same a constant distance away from the cutter, whereby the cutter is positioned solely by the engagement of the gage with the inseam stitches.
- 45 2. An inseam trimmer comprising a cutter, and a gage constructed to enter the stitch depressions of the inseam and guide the same at a constant distance from the cutter, whereby the cutter is positioned solely by the engagement of the gage with the inseam stitches.
- 50 3. An inseam trimmer comprising a cutter, and a gage provided with movable projections arranged to enter the depressions of the inseam of a shoe for guiding the same at a uniform distance from the cutter.

4. An inseam trimmer comprising a cutter, and a gage 55 wheel supported at a predetermined distance from the cutter and free to enter the inseam crease of a shoe and bear upon the stitches thereof, whereby the work may be guided solely by the wheel engaging said stitches to position the inseam stitches at a uniform distance from the cutter.

5. An inseam trimmer comprising a cutter, and a gage consisting of a freely rotatable wheel, mounted to engage the stitches of a shoe inseam, and position the cutter solely by the engagement of the wheel with said stitches.

6. An inseam trimmer comprising a cutter, and a freely 65 rotatable gage wheel mounted adjacent the cutter and free to engage the stitches of a shoe inseam, the wheel being provided with projections adapted to enter the stitch depressions.

7. An inseam trimmer comprising a cutter, and a gage 70 mounted for adjustment toward and from the cutter and arranged to engage the stitches of the inseam of a shoe, whereby the cutter is positioned solely by the engagement of the gage with the inseam stitches.

8. An inseam trimmer comprising a knife oscillatable in 75 a curved path, the edges of said knife being inclined relative to its path of oscillation, and a gage arranged to bear on the outer side of the inseam of a shoe and to support the work against the thrust of the knife edge, the operative stroke of the knife exerting pressure in a direction 80 toward the gage.

9. An inseam trimmer comprising a gage adapted to bear against the inseam of a shoe, and an oscillating knife having a cutting edge oblique to its path of motion and arranged to press the work against the gage, during 85 the cutting stroke, the operative stroke of the knife exerting pressure in a direction toward the gage.

10. An inseam trimmer comprising an oscillating knife blade curved circularly about its center of oscillation and having its cutting edge oblique to its path of motion, a 90 stop beside said blade adapted to bear upon the insole of a shoe, and a gage constructed and arranged to engage the stitches of the inseam of the shoe and guide the same at a uniform distance from the knife, and hold the work against the cutting pressure of the knife, the operative 95 stroke of the knife exerting pressure in a direction toward the gage.

11. An inseam trimmer comprising an oscillating knife blade curved circularly about its center of oscillation and having its cutting edge oblique to its path of motion, and 100 a gage consisting of a disk loosely pivoted in the plane of oscillation of the knife, the operative stroke of the knife exerting pressure in a direction toward the gage.

12. An inseam trimmer comprising an oscillating knife blade curved circularly about its center of oscillation and having its cutting edge oblique to its path of motion, and 105 a gage consisting of a disk loosely pivoted in the plane of oscillation of the knife and serrated at its periphery, the operative stroke of the knife exerting pressure in a direction toward the gage.

In testimony whereof I have affixed my signature, in presence of two witnesses.
